UNITED STATES PATENT OFFICE.

MELVILLE CLARK, OF CHICAGO, ILLINOIS.

AUTOMATIC PIANO.

No. 901,323.

Specification of Letters Patent. Patented Oct. 20, 1908.

Application filed May 22, 1907. Serial No. 375,004.

To all whom it may concern:

Be it known that I, MELVILLE CLARK, a citizen of the United States, residing at Chicago, in the county of Cook and State of Illinois, have invented new and useful Improvements in Automatic Pianos, of which the following is a specification, reference being had to the drawings forming a part thereof.

10 The purpose of this invention is to provide in an automatic piano a novel means for accenting particular notes and for controlling such accenting, either automatically or at will, and particularly by means of automatic control to produce the effect of distinguishing the melody from accompanying parts of the music.

It consists in the elements and features of construction shown and described as indicated in the claims.

In the drawings:—Figure 1 is a fore-and-aft vertical section of a portion of an automatic piano embodying this invention, the primary pneumatic action being broken away and shown in a vertical fore-and-aft plane at the same plane as Fig. 3. Fig. 2 is a section at the line 2—2 on Fig. 1. Fig. 3 is a detail fore-and-aft vertical section through the pneumatic action at the position 25 of the primary pneumatic which controls the tone softening devices, other parts being shown in the same plane as Fig. 1. Fig. 4 is a vertical right-and-left section of the lower part of the instrument showing the 30 construction for operating at will the soft pedal devices taken advantage of, section being made at the line 4—4 on Fig. 1. Fig. 5 is a detail front elevation of the motor pneumatic for operating the tone softening devices. Fig. 6 is a detail plan of a piece of 35 perforated note sheet adapted to be employed in this invention. Fig. 7 is a detail elevation showing the tracker board and adjacent parts having features peculiar to this 40 invention. Fig. 8 is a section at the line 8—8 on Fig. 7.

In the drawings the piano case and customary parts of the piano as constructed for manual operation are shown in accordance with familiar construction, and such parts will be referred to only so far as necessary to identify the relation thereto of the

parts peculiar to the invention, being referred to by their customary names.

The pneumatic devices for automatically 55 playing the piano comprise the pumbers, 1, and exhaust bellows, 2, mounted respectively above and below the foundation board, 3, all these parts being constructed as a unitary structure secured below the key table, 5, the 60 exhaust bellows being connected with the primary chamber of the pneumatic action, as fully described in my Patent No. 795,817, dated August 1, 1905, and said pneumatic action comprising the primary pneumatic 65 chamber, 6, and motor pneumatics, 7, and the customary operating connections (not shown in detail), being mounted above the key table, 5, and above the rear part of the 70 keys of the manual,—that is, rearward of the portion exposed for manual playing, said pneumatic action being in position, therefore, to be inclosed by the case of the piano, all of which may be clearly understood from Fig. 1. 75

In the particular feature of my invention which relates to accenting or melodizing, I take advantage of the means employed in the regular piano action, operated by the so-called soft pedals for softening the tone. 80 In the drawings I have illustrated my invention as applied to a piano action employing the means for this purpose which is most familiar, consisting in a hammer rest rail which is movable and connected with the 85 soft pedal for movement to limit the retreating movement of the hammers, and so to shorten the movement by which they strike the strings, thereby causing them to make the stroke with reduced velocity and 90 force. It will be understood that expedients beside the movable hammer rest rail, which are adapted to be operated by the soft pedal or any equivalent mechanical means, may be taken advantage of in the same way as, 95 in the construction herein described, advantage is taken of this movable hammer rest rail. I prefer to employ a divided hammer rest rail, one section operating over the right-hand or upper half of the manual, 100 while the other section operates over the left-hand or lower half. Each section, 8, of such divided hammer rest rail is carried by an arm, 8^a, having its pivot mounted

most conveniently at 9^a, on the end cheek, 9, of the case, and by an arm, 8^b, at the other end of the hammer rest rail section, pivoted on a bracket, 10, which may be secured to the sounding board, 11, trending thence forward and down to reach the proper point for pivoting the inner arms, 8^b, of the hammer rest rail thereto, as seen in Fig. 2. The outer hammer rest rail arms, 8^a, are in bell crank form, having each a forwardly extending arm, 8^c. On the primary pneumatic chamber, 6, adjacent to the cheek, 9, of the case there is mounted a motor pneumatic, 12, which is connected by a flexible tube, 13, with the corresponding primary pneumatic, 14, in the primary pneumatic chamber, 6, at the end of the series of primary pneumatics therein, and from said primary pneumatic, 14, a duct, 15, extends to the tracker mouth, as hereinafter more particularly described. The primary pneumatic, 14, differs from the ordinary primary pneumatic which controls the motor pneumatics for operating the key strikers, in that the valve, 16, which it operates for controlling communication of the motor pneumatic, 12, with the exhaust air chamber and with the atmosphere respectively is normally in position closing the communication by way of the port, 17, with the atmosphere, leaving open the port, 18, which puts the motor pneumatics in communication with the exhaust air. Whenever the instrument is in use for automatic playing, so that there is exhaust tension developed in the exhaust bellows, 2, the motor pneumatic, 12, will be collapsed. The moving wall of this pneumatic is connected with the arm, 8^c, of the bell-crank-lever arm, 8^a, of the hammer rest rail, so that it holds that arm upward and the hammer rest rail rocked inward toward the sounding board, 11, whenever the pneumatic, 12, is thus collapsed. The normal action of the instrument when played automatically will therefore be such as to play with only moderate intensity, due to the shortened stroke of the hammers, 20.

At each margin of the perforated sheet, 25, there may be cut short apertures, 25^a, for registering with the mouth of a tracker duct, 26^b, to which is connected the flexible tube, 15, leading to the primary pneumatic, 14, which controls the motor pneumatic, 12. Whenever such an aperture, 25^a, registers with the tracker mouth, 26^b, and admits air to the primary pneumatic, 14, the valve, 16, is shifted so as to put the pneumatic, 12, in communication with the atmosphere, causing it to be inflated, retracting the hammer rest rail so as to allow the hammers, 20, a longer stroke. When this expedient is employed for the purpose of emphasizing the entire chord, all the apertures of the perforated sheet for that chord are cut with their for-

ward edges in line, and the apertures, 25^a, 65 also in line with them. When it is employed for the purpose of emphasizing particular notes in the chord, as for distinguishing the melody from the accompaniment, the apertures, 25^b, for the melody are cut slightly in 70 advance of the remaining apertures of the chord, and the aperture, 25^a, is cut similarly in advance so as to be in line with the commencement of the apertures, 25^b. The effect 75 of this arrangement of the apertures, it will be seen, is that the hammer rest rail is retracted to position for allowing the hammers, 20, their full stroke just long enough to cause the aperture for the melody note to reach its proper tracker mouth and admit 80 the air to the primary pneumatic controlling the proper striker, so that the motor pneumatic for operating that striker will receive its impulse and actuate the striker while the hammer rest rail is in retracted position; 85 but immediately thereafter, and before the stroke is actually received by the string, the aperture, 25^a, passing beyond its tracker mouth, the latter will be closed, the motor pneumatic, 12, will be again exposed to the 90 exhaust tension and collapsed, the hammer rest rail will be restored to the advanced position, and will be at that position when the remaining notes of the chord are caused to be struck by the registration of the remaining apertures of the note sheet for that chord reaching their respective tracker mouths. When a piece is cut for emphasizing the melody throughout, an aperture, 25^a, will be 95 cut on the margin of the sheet at the commencement of each chord,—that is, for each note of the melody,—and the apertures for the several notes of the melody will all be 100 cut in advance of the remaining apertures of the chords in which they stand, so that 105 throughout the entire playing the melody note will be struck almost imperceptibly in advance of the remaining notes of the chord, and with a full stroke, while the remainder of the chord will be sounded more softly by 110 reason of the softer stroke of the hammers, 20. The division of the hammer rest rail, and the provision of marginal apertures, 25^a, at both margins of the sheet makes it possible 115 to emphasize notes falling in either the lower or the upper half of the range of the instrument; and with this construction, when a melody runs both sides of the division line the marginal aperture, 25^a, will be cut at one side or the other, according to the position of 120 the particular note to be influenced with respect to said divisional line, but when the purpose is to emphasize either the bass or the treble notes without regard to melody, all the apertures, 25^a, will be cut on one side or 125 the other, according to the part to be emphasized. When this expedient is to be employed for emphasizing the accented beat of

the measure throughout the entire chord on which said accented beat falls, it will be understood that the perforations of the sheet will all be cut in line, and the marginal aperture, 25^a, in line with them also, such perforations being located only opposite the notes of the accented chords. When the sheet is not cut for automatically accenting in this manner, the instrument may be employed for 10 that purpose by means of the manually operated vent stop, 28. This vent stop which is preferably located, as shown, under the forward edge of the key table in reach of the operator, operates a valve, 29, which normally closes and is operated by the stop to open the mouth of a duct, 30, which is connected by a flexible tube, 31, with the primary pneumatic, 14, said flexible tube, 31, being conveniently joined to the flexible tube, 15, by means of a Y, 32, at any convenient point, as illustrated. The manual operation of this stop, it will be understood, has the same effect as the automatic operation of the aperture, 25^a, in the perforated sheet uncovering the mouth of the tracker duct admitting air through the tube, 15, to the primary pneumatic, 14. When the operator desires the entire piece or any extended portion of it played loudly or with the full force of 20 which the instrument is capable, the stop, 28, will be held open, and for convenience it may be provided with means for locking it open, consisting of an eccentric cam, 28^a, which may be rocked to the dotted line position 30 illustrated for that purpose.

The devices described for operating the hammer rest rail to automatically or at will vary the force of any particular note or chord do not interfere with the use of the 40 instrument when operated manually, for it will be observed that whenever the action of the pumbers ceases, so that there is no exhaust tension produced in the bellows, 2, the motor pneumatic, 12, will be inflated whatever be the position of the valve, 16, and the hammer rest rail will therefore, under such circumstances,—that is, with the instrument not in automatic use,—be at its retracted position, allowing the hammers, 20, full 50 stroke. The customary means for operating the hammer rest rail by the soft pedals is not interfered with by the devices above described. Said customary means or a means which may stand for any customary means 55 of operating the haunner rest rail by the so-called "soft" pedal, is shown in the drawings, consisting of the levers, 40, 40, extending right and left at the lower part of the instrument, being fulcrumed at 41, 41 on 60 any convenient supports, as the brackets, 42, said levers being arranged so that at their inner ends they extend past each other for a short distance and are both crossed by the soft pedal lever, 43, the depression of which

carries down the inner ends of both said 65 levers, 40, causing their outer ends to be lifted and to thrust upward the pitman rods, 44, 44, which operate in proper guides, 45, mounted on the cheeks, 9, 9, and which impinge at their upper ends under the arms, 70 8^a, 8^c, of the bell-crank-lever arms, 8^a, on the respective sections of the hammer rest rail. The connections of this soft pedal action, it will be observed, are such that none of the parts concerned therein are actuated in the 75 pneumatic actuation of the hammer rest rail: that is to say, the pneumatics, 12, do not have to lift the pitmen, 44, nor operate the levers, 40. In order to give the hammer rest rail quick action in its retraction for 80 loud stroke, as well as in its advance for soft stroke, a light spring, 46, may be employed tending to rock it back. It will be stopped at the limit of such rocking action by the lodgment of the arm, 8^c, on the upper end 85 of the pitman, 44, and no other stop need be provided when the pitman is present.

When a controller sheet of the character described is employed in connection with the tracker board which is mounted for 90 longitudinal adjustment,—that is, for adjustment transversely with respect to the direction of travel of the controlling sheet,—for transposition, it is desirable to make provision for preventing such adjustment 95 from displacing relatively to each other the lateral apertures, 25^a, of the controlling sheet, and the corresponding duct mouths, 26^b, of the tracker board, since these elements should register properly at all times without 100 regard to the transposition. In Figs. 7 and 8 there is shown a familiar construction of tracker board mounted for adjustment for transposition as described, guides, 50, mounted on the cheeks, 9, serving to position and retain the tracker board, 51, which is provided with a rigid stem, 52, extending through one cheek and having an offset arm, 53, which is engaged by a screw, 54, mounted on the cheek and rotated by means of its 105 head, 55, to adjust the tracker board longitudinally. At the two ends of the tracker board, 51, between the guide plates, 50, there are mounted supplemental blocks, 56, having the ducts, 26^b, and these blocks, it will be observed, are not moved with the tracker board when the latter is adjusted for transposition, and the apertures, 25^a, of the controlling sheet therefore may register with the duct mouths, 26^b, throughout the entire range 110 120 of longitudinal adjustment of the tracker board.

I claim:

1. In an automatic piano, in combination with the sounding devices, a tone-modifier 125 constructed for operating simultaneously with respect to an extended group of consecutive sounding devices; auto-pneumatic

playing devices comprising a tracker and a traveling controlling sheet, the tone modifier being adapted when the autopneumatic playing devices are out of service to assume a certain position with respect to the sounding devices; a motor pneumatic and connections by which when the auto-pneumatic playing devices are in service it holds the tone-modifier at a different position; a primary pneumatic for controlling such motor pneumatic; said tracker board and controlling sheet having respectively a supplemental duct and short supplemental apertures coöperating therewith for causing action of the motor pneumatic to momentarily release the tone-modifier controlling said primary pneumatic, such supplemental apertures and the commencement of the apertures for the notes to be affected by the release of the tone-modifier being cut out of time with the other apertures in their respective chords.

2. In an automatic piano, in combination with the sounding devices, a tone-modifier constructed for operating simultaneously upon an extended group of consecutive sounding devices; auto-pneumatic playing devices comprising a tracker and traveling controlling sheet; a motor pneumatic and connections by which when the auto-pneumatic playing devices are in service it holds the tone-modifier normally at a position for softening the tone, said tone-modifier being adapted when released from said motor pneumatic to assume a position for intensified tone; a primary pneumatic for controlling such motor pneumatic, the tracker board and controlling sheet having respectively a supplemental duct and supplemental apertures coöperating therewith for controlling such primary pneumatic, such supplemental apertures and the commencement of the apertures for the notes to be affected by the release of the tone-modifier being cut out of time with the other apertures in their respective chords.

3. In an automatic piano, in combination with sounding devices, a tone-modifier constructed for operating simultaneously upon an extended group of consecutive sounding devices; auto-pneumatic playing devices comprising a tracker and a traveling controlling sheet; a motor pneumatic and connections by which when collapsed it holds the tone modifier at tone-softening position, said tone-modifier being adapted to assume a tone-intensifying position when free from the action of said motor pneumatic; a primary pneumatic and valve connections by which it causes the motor pneumatic to be collapsed when said primary pneumatic is collapsed and expanded when the primary pneumatic is expanded, the tracker board and controlling sheet having respectively a supplemental duct and supplemental ap-

tures coöperating therewith for controlling said primary pneumatic, such supplemental apertures and the commencement of the special apertures for notes to be affected being cut out of time with the other apertures in their respective chords.

4. In an auto-pneumatic piano, in combination with the piano action comprising tone-modifying devices, automatic playing devices comprising a tracker and a traveling perforated controller sheet; pneumatically-operated and controlled means for operating the tone-modifying devices, comprising a supplemental tracker duct and supplemental apertures in the controller sheet coöperating with such duct, the tracker and the traveling sheet being mounted for change of relative position transversely with respect to the direction of travel of the sheet, the supplemental tracker duct being formed in a part which is mounted for preserving unchanged its position relative to the controller sheet in such change of relative transverse position of the tracker and sheet.

5. In an automatic piano, in combination with the tone-modifying devices of the piano action, automatic playing devices pneumatically operated and controlled; means for operating the tone-modifying devices, said means comprising a supplemental tracker duct and supplemental apertures in the controller sheet coöperating therewith, the tracker board being mounted for movement transverse of the direction of travel of the controller sheet, the supplemental tracker duct being formed in a part which is mounted for preserving its position unchanged in such transverse movement of the tracker board.

6. In an automatic piano, in combination with tone-modifying devices of the piano action; auto-pneumatic playing devices; a motor pneumatic and controlling means for the same; connections by which when the auto-pneumatic playing devices are in service said motor pneumatic holds the tone modifier in tone-softening position, said tone modifier being adapted to withdraw from such position when released from the action of such motor pneumatic; a primary pneumatic for controlling the motor pneumatic, valve connections by which such control is effected arranged for admitting atmospheric air to the motor pneumatic when the primary pneumatic is operated by the controlling sheet; a supplemental duct in the tracker board and supplemental apertures in the controlling sheet coöperating therewith for controlling said primary pneumatic.

7. In an automatic piano, in combination with the tone-softening devices of the piano action, auto-pneumatic playing devices; a motor pneumatic and connections therefrom for holding the tone-softening devices nor-

mally in tone-softening position when the auto-pneumatic action is in service; a primary pneumatic and valve operated thereby, for controlling said motor pneumatic adapted
5 normally when the primary pneumatic is not inflated to give the motor pneumatic communication with the exhaust chamber of the auto-pneumatic action for holding said motor pneumatic collapsed; a supplemental tracker
10 duct and supplemental perforations in the controller sheet coöperating with such duct

for controlling such primary, such supplemental aperture and the apertures for the notes to be emphasized being cut in advance of the other apertures of the chord.

15

In testimony whereof, I have hereunto set my hand at Chicago, Illinois, this 20th day of May, 1907.
